RAILWAY SIGNALING

Ronald A. McCann, Swissvale, Pa., assignor to
The Union Switch & Signal Company, Swiss-
vale, Pa., a corporation of Pennsylvania

Application March 6, 1936, Serial No. 67,467

19 Claims. (Cl. 246—50)

My invention relates to railway signaling and particularly to signaling involving wayside signals located along a trackway for governing the passage of trains.

The apparatus of this invention is an improvement over that disclosed in application Serial No. 26,784, of James J. Vanhorn, filed June 15, 1935, for Railway signaling.

A feature of my invention is the provision of 10 novel and improved apparatus for establishing a distinctive control for each of three sections in the rear of an occupied section. Each distinctive control is effective to cause a corresponding aspect of the associated wayside signal, whereby there is 15 produced a three-block, four-indication system of signaling.

I will describe one form of apparatus embodying my invention, and will then point out the novel features thereof in claims.

20 In the accompanying drawings, Figs. 1A and 1B are diagrammatic views which, when placed end to end in the order named, illustrate one form of apparatus embodying my invention.

Referring to the drawings, the reference characters 25 8 and 9 designate the rails of a stretch of railway track along which traffic normally moves in the direction indicated by the arrows. These rails are divided by insulated joints 14 into a plurality of track sections or blocks W—X, X—Y, 30 and Y—Z.

Each track section is divided by insulated joints 14 into at least two sub-sections 1T, 2T, 3T, 4T, etc. Each sub-section is provided with a track circuit which includes a track battery 15 connected across the rails at one end of the sub-section and a track relay, designated by the reference character TR with a prefix the same as the numerical prefix in the reference character of the associated sub-section, connected across the rails 40 at the other end of the sub-section.

To govern the passage of trains through the stretch of railway, a wayside signal, designated by the reference character S with a suitable distinguishing prefix, is provided for each track section. Each of these signals comprises a top unit T and a lower unit L. These units may take any one of several forms of signal mechanisms such as semaphore, color light, searchlight, or position light. As here shown, each top unit is a semaphore arm capable of assuming three positions and each lower unit is a semaphore arm capable of assuming two positions. That is, the top arm has a horizontal or "stop" position, a 45° or "caution" position, and a vertical or "proceed" 55 position, and the lower arm has a horizontal or

"stop" position and a vertical or "proceed" position. Each semaphore arm assumes its horizontal position when deenergized.

Each section is provided with a direct current polarized signal control relay designated by the 5 reference characters HD with a prefix the same as the prefix in the reference character of the associated signal.

Each section is also provided with an alternating current neutral signal control relay designated by the reference character H with a prefix 10 the same as the prefix in the reference character of the associated signal.

Each direct current relay HD is connected to a two-wire line circuit over a back contact of the associated alternating current relay H, and the associated neutral alternating current relay H is connected to the same line circuit through a condenser designated by the reference character Q with a prefix the same as the prefix in the reference 20 character for the associated signal. It will be apparent, therefore, that the condenser Q will prevent the energization of the alternating current relay H by direct current and the contact of the alternating current relay H will prevent the 25 energization of the direct current relay HD when the alternating current relay H is energized.

Each section is provided with an alternating current transfer relay designated by the reference character GP with a prefix the same as the prefix 30 in the reference character of the associated signal. Each relay GP when energized is effective to supply alternating current to the line circuit for the section next in rear and when deenergized is effective to supply direct current to that line circuit. 35

Operably connected to each top semaphore arm T is a pole changer designated by the reference character P with a prefix the same as the prefix in the reference character for the associated signal. Each pole changer P occupies its normal condition when the associated semaphore arm is in its caution position or in its vertical position or at any point between these two positions, and occupies its reverse condition when such arm is 45 at any point below the caution position. Also operably connected to each top semaphore arm T is a contact 18—18A closed only when the arm is in its caution position and a contact 19—19A which is closed when the arm is in its caution 50 position or its vertical position or at any point between these two positions. Operably connected to each lower semaphore arm L is a contact 20—20A which is closed only when that arm is in 55 its vertical position.

Each top semaphore arm T and each lower semaphore arm L is provided with a lamp TE and LE, respectively, for displaying supplementary color light indications corresponding to the position of the associated semaphore arm. The lamps TE and LE at each signal are controlled by an approach lighting relay designated by the reference character ER with a prefix the same as the prefix in the reference character of the associated signal. The approach lighting relay for each signal is included in series with the line circuit for the section next in rear and is so controlled as to become energized whenever the associated line circuit is energized either by direct current or alternating current and to become deenergized only when that line circuit is opened; that is, when a train is approaching the signal. Each approach lighting relay is provided with a shunt path including a rectifier R which is so poled and controlled that when the associated line circuit is energized with alternating current the rectifier is effective to bypass one-half of the alternating current wave so that the approach lighting relay is energized in one direction only and when the line circuit is energized with direct current the rectifier is disconnected from the shunt path around the approach lighting relay so that all of the direct current must pass through the relay. Referring to signal 12S, for example, it will be noted that since relay 12GP is energized so that its front contact 62 becomes closed, the rectifier 12R will be effective for bypassing one-half of the alternating current wave. The approach lighting relay 12ER, therefore, will be energized in one direction and will maintain its back contact 63 opened so that the lamps TE and LE for signal 12S will not become lighted. When relay 12GP is deenergized so that its front contact 62 becomes opened, the rectifier 12R is no longer connected across the relay 12ER. Regardless of the polarity of the line circuit, therefore, relay 12ER will be energized by direct current so that its back contact 63 remains opened. When a train enters section W-X so that the line circuit for that section becomes opened, then relay 12ER will become released. When relay 12ER is released so that its back contact 63 becomes closed, the lamps TE and LE of signal 12S will become lighted to provide a light indication corresponding to the indication displayed by the position of the semaphore arms.

For supplying the direct current and alternating current energy, each section is provided with a suitable source of direct current energy, the terminals of which are designated by the reference characters B and C; and each section is provided with a suitable source of alternating current energy, the terminals of which are designated by the reference characters BX and CX.

The manner in which the signals are controlled to cause the display of the different aspects will best be understood by tracing the circuits and explaining the operation of the apparatus simultaneously.

A train K is here shown occupying the section immediately to the right of location Z so that the line circuit for the control of relays 14H and 14HD is opened.

Signal 14S, therefore, is displaying both its semaphore arms T and L in the horizontal position to indicate "stop".

With signal 14S in this condition, pole changer 14P is occupying its reverse position and relay 14GP is deenergized.

The polarized direct current relay 13HD is energized in the reverse direction by a circuit which

passes from terminal B of the source of direct current at signal 14S, through contact 24 of pole changer 14P, back point of contact 25 of relay 14GP, front contact 26 of track relay 6TR, front contact 27 of track relay 5TR, relay 13HD, back contact 28 of alternating current relay 13H, front contact 29 of track relay 5TR, front contact 30 of track relay 6TR, approach lighting relay 14ER, back point of contact 31 of relay 14GP and contact 32 of pole changer 14P to terminal C of the same source of direct current.

Since relay 13HD is energized in the reverse direction, a caution circuit for the top semaphore arm T of the signal 13S is energized by current which passes from terminal B through front contact 33 of relay 13HD and semaphore arm T to terminal C. The signal 13S, therefore, is displaying its top semaphore arm in the caution position and its lower semaphore arm in the horizontal position to indicate "approach next signal prepared to stop".

The polarized direct current relay 12HD is energized in the normal direction by a circuit which passes from terminal B, at signal 13S, through contact 38 of pole changer 13P, back point of contact 39 of relay 13GP, approach lighting relay 13ER, front contact 40 of relay 4TR, front contact 41 of relay 3TR, back contact 42 of relay 12H, relay 12HD, front contact 43 of relay 3TR, front contact 44 of relay 4TR, back point of contact 45 of relay 13GP, and contact 46 of pole changer 13P to terminal C.

Since relay 12HD is energized in the normal direction, the caution circuit for the top semaphore arm T of signal 12S is energized over front contact 47 of relay 12HD; and a clear circuit for the lower semaphore arm is energized by current which passes from terminal B through front contact 47 of relay 12HD, normal polar contact 34-35 of relay 12HD, contact 18-18A of top semaphor arm T, and lower semaphor arm L to terminal C. The signal 12S, therefore, is displaying its top semaphore arm in the caution position and its lower semaphore arm in the vertical position to indicate "approach next signal at medium speed".

The transfer relay 12GP is energized over a circuit which passes from terminal BX of the source of alternating current, at signal 12S, through contact 28-20A of lower semaphor arm L of signal 12S, contact 19-19A of top semaphor arm T and relay 12GP to terminal CX of the same source of alternating current.

Since relay 12GP is energized, neutral alternating current relay 11H is energized by alternating current over a circuit which passes from terminal BX, at signal 12S through front point of contact 50 of relay 12GP, approach lighting relay 12ER, front contact 51 of relay 2TR, front contact 52 of relay 1TR, relay 11H, condenser 11Q, front contact 53 of relay 1TR, front contact 54 of relay 2TR, and front point of contact 55 of relay 12GP to terminal CX.

Since relay 11H is energized, both the caution circuit and the clear circuits for the top semaphore arm T of signal 11S are energized over front contacts 57 and 58, respectively; and since relay 11HD is deenergized the lower semaphor arm L is deenergized because front contact 59 of relay 11HD is opened. The signal 11S, therefore, is displaying its top semaphore arm in the vertical position and its lower semaphore arm in the horizontal position to indicate "proceed at normal speed".

The transfer relay 11GP is energized over a

circuit which passes from terminal BX through front contacts 60 of relay 11H, contact 19-19A of top semaphore arm T of signal 11S and relay 11GP to terminal CX. The line circuit for the section next in rear of signal 11S, therefore, is supplied with alternating current so that the signal (not shown) for the section next in rear is displaying the "proceed at normal speed" indication.

5. When the train K vacates the section immediately to the right of location Z, the line circuit for the control of signal 14S will be then supplied with direct current energy in the reverse direction so that that signal will display its top semaphore arm in the caution position and its lower semaphore arm in the horizontal position to indicate "approach next signal prepared to stop".

When signal 14S is in this condition, the line circuit for the control of signal 13S will be then energized by direct current of normal polarity so that signal will display its top semaphore arm in the caution position and its lower semaphore arm in the vertical position to indicate "approach next signal at medium speed".

When signal 13S is displaying this indication, relay 13GP will become energized so that the line circuit for the control of signal 12S will be then supplied with alternating current energy over front points 39 and 45 of relay 13GP to cause signal 11S to display the normal proceed indication.

It will be noted that in the event of the absence of the alternating current source of power the line circuits will be supplied with direct current so that signal indications will be provided to keep traffic moving. For example, if the alternating current source of power at signal 12S should fail, the transfer relay 12GP would become released so that direct current of normal polarity would be supplied to the line circuit for signal 11S and that signal would change its indication from "proceed at normal speed" to "approach next signal at medium speed".

45. It will also be noted that but two line wires are required between signals.

It will be apparent, therefore, that the apparatus embodying my invention provides a simple, reliable and economical means for controlling a three-block, four-indication, system of signaling.

50. Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, two successive sections of railway track, a signal for the forward section having a first semaphore arm capable of assuming a caution position as well as a vertical and a horizontal position, said signal also having a second semaphore arm capable of assuming a vertical and a horizontal position, means for causing said signal to assume its different positions in accordance with traffic conditions in advance of the signal, a contact closed when the first arm occupies either its caution or its vertical position, a contact closed when the second arm occupies its vertical position, a relay, a circuit for said relay including said two contacts, a pair of conductors including contacts of said relay, and a signal for the rear section controlled by said conductors.

2. In combination, two successive sections of railway track, a signal for the forward section having a semaphore arm operable to different positions, said semaphore arm normally occupying a vertical position, a normally energized relay 5 for controlling said signal in accordance with traffic conditions in advance of the signal, another relay, a circuit for said other relay including a front contact of said normally energized relay and a contact closed when the said semaphore arm occupies its vertical position, a circuit controlled by traffic conditions in said rear section, said circuit being supplied with alternating current when said other relay is energized and with direct current when said other relay 15 is deenergized, an alternating current relay and a direct current relay both connected to said circuit, and a signal for the rear section controlled by said two relays.

3. In combination, two successive sections of railway track, a signal for the forward section having a first semaphore arm and a second semaphore arm, said first arm capable of assuming a caution position as well as a vertical and a horizontal position and said second arm capable of 25 assuming a vertical and a horizontal position, means for controlling said signal in accordance with traffic conditions in advance of said section, a contact closed when the first arm occupies its caution position, a circuit for the second arm 30 including said contact, another contact closed when the second arm occupies its vertical position, a relay, a circuit for said relay including said other contact, a circuit controlled by traffic conditions in said rear section, said circuit being 35 controlled by said other relay, and a signal for the rear section controlled by said circuit.

4. In combination, two successive sections of railway track, a signal for the forward section, a source of alternating current, an alternating 40 current relay which is deenergized when said signal displays certain indications and which is energized when said signal displays certain less restrictive indications provided said alternating current is present, a pole changer operably governed by said signal and connected to a source of direct current, a circuit which is connected to said pole changer when said relay is deenergized and which is connected to said source of alternating current when said relay is energized, 50 said circuit being controlled by traffic conditions in said rear section, a direct current polarized relay and a neutral alternating current relay both controlled by said circuit, and a signal for the rear section controlled by said two relays. 55

5. In combination, two successive sections of railway track, a signal for the forward section having a lamp and controlled by traffic conditions in that section, a pole changer controlled by said signal and connected to a source of direct 60 current, a source of alternating current, a circuit for the rear section controlled by traffic conditions in said section, a relay controlled by said signal for connecting said circuit with either said pole changer or said source of alternating current, an approach lighting relay responsive to either direct current or alternating current and connected in said circuit for controlling said lamp, and signaling means for the rear section controlled by said circuit.

6. In combination, a railway signal including a lamp, a circuit controlled by traffic conditions in rear of said signal, a direct current relay connected in said circuit for controlling said lamp, a source of direct current, a source of alternat- 75

ing current, a normally energized alternating current relay which becomes deenergized when said alternating current source is absent, means including contacts of said alternating current relay for supplying said circuit with either alternating current or direct current according as said alternating current relay is energized or deenergized respectively, and means including a rectifier for causing said direct current relay to become responsive to alternating current.

7. In combination, a section of railway track having a pair of conductors governed by traffic conditions in said section, a signal for said section capable of assuming several distinctive aspects, a direct current polarized relay and an alternating current neutral relay for jointly controlling the different aspects of said signal, said relays being supplied with current from said pair of conductors, and means selectively governed by traffic conditions in advance of said section for supplying direct current of one polarity or direct current of the other polarity or alternating current to said conductors but not both direct and alternating current simultaneously.

8. In combination, a section of railway track having a pair of conductors governed by traffic conditions in said section, a polarized direct current relay and a neutral alternating current relay both receiving energy from said conductors, means selectively governed by traffic conditions in advance of said section for supplying to said conductors direct current of normal polarity or direct current of reverse polarity or alternating current but not both direct current and alternating current simultaneously, and traffic governing means for said section controlled by said two relays.

9. In combination, a section of railway track, a pair of conductors governed by traffic conditions in said section, a direct current polarized relay and an alternating current neutral relay both receiving energy from said conductors, means governed by traffic conditions in advance of said section for supplying either alternating current or direct current of one polarity or the other polarity but not both direct current and alternating current simultaneously to said conductors, means for preventing the energization of said direct current relay when said alternating current relay is energized, means for preventing the energization of said alternating current relay when said conductors are supplied with direct current, and a traffic governing device controlled by said two relays.

10. In combination, a section of railway track, a pair of conductors governed by traffic conditions in said section, a direct current relay and an alternating current relay both receiving energy from said conductors, means governed by traffic conditions in advance of said section for supplying either alternating current or direct current but not both simultaneously to said conductors, means including a back contact of said alternating current relay for preventing the energization of said direct current relay when the alternating current relay is energized, means including a condenser for preventing the energization of said alternating current relay when said conductors are supplied with direct current, and traffic governing means controlled by said two relays.

11. In combination, a section of railway track, a pair of conductors governed by traffic conditions in said section, a signal for said section, a

5 direct current relay and an alternating current relay both for governing said signal, means including a condenser for connecting said alternating current relay to said conductors, means including a contact of said alternating current relay for connecting said direct current relay to said conductors, and means governed by traffic conditions in advance of said section for supplying either alternating current or direct current to said conductors.

10 12. In combination, a section of railway track, a pair of conductors governed by traffic conditions in said section, a signal in advance of said section, a pole changer supplied with a source of direct current and operably connected to said signal, a relay which when energized supplies alternating current to said conductors and when deenergized connects said pole changer to said conductors, means for energizing or deenergizing said relay depending upon the condition of said signal, and signaling means for said section controlled by said conductors and selectively responsive to alternating current and direct current.

15 13. In combination, two successive sections of railway track each such section having a pair of conductors governed by traffic conditions in said section, a signal for the forward section controlled by the conductors for that section and capable of displaying four distinctive aspects including a proceed aspect and an approach medium aspect as well as an approach aspect and a stop aspect, a relay which is energized when said signal is displaying either the proceed or the approach medium aspect and which is deenergized when said signal is displaying either the approach or the stop aspect, means controlled by said relay according as said relay is energized or deenergized for supplying alternating current or direct current to the pair of conductors for the rear section, an alternating current relay and a direct current relay both connected to said conductors for the rear section, and a signal for the rear section controlled by said two relays.

20 14. A railway signaling system comprising a stretch of track divided into sections each having a pair of conductors governed by traffic conditions in said section, two relays for each section one polarized direct current relay and one neutral alternating current relay and both connected to the associated conductors, means controlled by said two relays for each section for selectively supplying to the conductors for the section next in rear direct current only of normal polarity or direct current only of reverse polarity or for supplying alternating current only; and a signal for each section controlled by said two relays of that section and arranged to have a first aspect when both relays are deenergized, a second aspect when the direct current relay is energized reverse and the alternating current relay is deenergized, a third aspect when the direct current relay is energized normal and the alternating current relay is deenergized, and a fourth aspect when the direct current relay is deenergized and the alternating current relay is energized.

25 15. In combination, a section of railway track having a pair of conductors governed by traffic conditions in said section, a signal for each section, said signal having a first unit capable of displaying three different conditions and a second unit capable of displaying two different conditions, a polarized direct current relay and a neutral alternating current relay energized from said pair of conductors and controlling said sig- 75

nal, means responsive to traffic conditions in advance of said section for supplying said pair of conductors with direct current of normal or with direct current of reverse polarity or with alternating current, a circuit including a front contact of said direct current relay for causing said first unit to assume one condition, another circuit including a front contact of said alternating current relay also for causing said first unit to assume said one condition, a circuit including another front contact of said alternating current relay for causing said first unit to assume a different condition and a circuit including a normal polar contact and a front contact of said polarized relay for causing said second unit to assume one condition provided said first unit then occupies a particular condition.

16. In combination, a railway signal including a lamp, a circuit controlled by traffic conditions in rear of said signal, a relay for controlling said lamp and connected in said circuit, a source of direct current, a source of alternating current, another relay controlled in accordance with traffic conditions in advance of said signal for connecting said circuit to the direct current source or the alternating current source, a rectifier, and a shunt path across the winding of said one relay and including said rectifier as well as a contact of said other relay.

17. A railway signal system comprising a stretch of railway track divided into a plurality of track sections, a pair of conductors for each section governed by traffic conditions in said section, a polarized direct current relay for each section receiving energy from the associated conductors, an alternating current relay also receiving energy from the associated conductors, means controlled by the two relays for selectively supplying alternating current only or direct current only of one polarity or of the other polarity to the conductors for the section next in rear of the associated section whereby a distinctive control is effected for each of three consecutive track sections next in rear of an occupied section.

18. In combination, a stretch of railway track

divided into a plurality of successive block sections a pair of conductors for each section governed by traffic conditions in said section, a signal for each section capable of assuming several different aspects, each signal having associated therewith a direct current polarized relay and an alternating current neutral relay jointly controlling the different aspects of said signal, said relays being supplied with energy from the pair of conductors for the section with which said signal is associated, and means controlled jointly by said relays for supplying direct current of one polarity or direct current of the other polarity or alternating current but not both direct and alternating current simultaneously to the pair of conductors for the adjacent block section in the rear of the section with which said relays are associated.

19. In combination, a stretch of railway track divided into a plurality of successive block sections each having associated therewith a pair of conductors governed by traffic conditions in said section, a signal for each section capable of displaying a stop indication and a plurality of different proceed indications having varying degrees of speed restriction, each signal having associated therewith a direct current polarized relay and an alternating current neutral relay supplied with current from the pair of conductors for the section with which the signal is associated, said relays jointly controlling the signal with which they are associated and the supply of direct current of normal or reverse polarity and also jointly controlling the supply of alternating current to the pair of conductors for the adjacent block section in the rear, the control of the signal by the relays associated therewith being arranged in such a manner that the direct current relay alone is effective to condition the signal to display at least one of its restrictive proceed indications, whereby said signal will not be caused to display a stop indication as a result of the absence of alternating current.

RONALD A. McCANN. 45
